UNITED STATES PATENT OFFICE.

EDWARD A. BUCKMAN AND TERRILL F. MORSON, OF SANTA ANA, CALIFORNIA.

INTERNAL-COMBUSTION ENGINE.

Application filed May 29, 1926. Serial No. 112,579.

This invention relates in general to internal combustion engines, and more particularly to what is known as a two-cycle internal combustion engine, and has as a principal object the provision of a cylinder having two concentric bores of different diameter, a reciprocable sleeve valve having portions of corresponding diameter fitting said cylinder, and a duplex piston reciprocat-
bly mounted in the sleeve and having portions fitting the different diameters thereof, whereby a power impulse may be imparted to the engine once in each revolution of the crank shaft, and on each down stroke of the piston, and a charge of fuel may be admitted to the cylinders during the power stroke, and the same compressed on the up-
stroke of the piston during the scavenging of the products of combustion from the cylinder.

Another object is to provide in an engine of the character mentioned means for introducing a charge of gas or fuel into an annular chamber within the major bore of the sleeve valve, and above the major portion of the piston during the power stroke of the piston, and means for scavenging the cylinder of the burnt gas, when the charge of fresh gas is admitted to the combustion chamber.

A further object is to provide a duplex cylinder having a sleeve valve and piston arrangement, in which the gas is sealed off from the crank case of the motor, and a charge of gas is admitted to the large bore of the cylinder, and thence transferred to a storage chamber above the upper bore of the cylinder, under compression, said storage chamber being in turn closed by the sleeve valve while the gas at the head of the piston is being finally compressed for imparting a power stroke to the piston at each revolution of the crank shaft, and for scavenging the cylinder of the burnt gases prior to the admission of fresh gas for another cycle of operation.

Other and more detailed objects of invention will appear as the description progresses.

In the accompanying drawings I have shown a preferred embodiment of my invention, subject to modification within the scope of the appended claims without departing from the spirit thereof, in which:

Fig. 1 is a transverse sectional elevation of a preferred form of internal combustion

engine, made in accordance with our invention.

Fig. 2 is a side elevation of a piston embodied in said invention.

Fig. 3 is a perspective view of the sleeve valve forming a part thereof.

Fig. 4 is an elevation, principally in section, in a plane at right angles to Fig. 1, showing the assembled engine.

Briefly described, our invention embodies a crank case or base member B, on which is mounted, as is customary in the manufacture of internal combustion motors, a cylinder block C, which is attached to the crank case by means of a plurality of bolts 1, 1, etc. The cylinder C is bored in the upper portion thereof at 2, and in the lower portion at 3 to receive a duplex sleeve valve member V, with an upper cylindrical portion 4, and a lower cylindrical portion 5 of substantially larger diameter than the portion 4, but integrally formed therewith and connected by means of a plurality of horizontally disposed connecting ribs 6, 6', as shown in Fig. 3. Portions 4 and 5 of the valve are of diameters corresponding to the bores 2 and 3 of the cylinder, respectively.

The ends of the valve V are open in each case, and the portions 4 and 5 are bored at 6 and 7, respectively, to receive portions 8 and 9 of a duplex piston P. Also, the cylinder block C is provided at its upper end with an annular gas storage chamber 9', and a valve seat 10 thereabove corresponding in diameter to the bore 2 in the cylinder, so as to receive the upper end of portion 4 of the sleeve valve V for closing the storage chamber 9' during certain intervals in the operation of the engine.

The cylinder C is provided with a water compartment 11 between the outer wall 12 thereof, the inner cylindrical wall 13, and the head 14, and a spark plug A of usual character is concentrically mounted in the head 14 and projects into the combustion chamber 15 of the cylinder. A gas intake I is attached to the cylinder block C at a point below the bore 2 therein, and an intake port or passage 16 is provided in the cylinder block for communication with said intake and preferably extends for a distance around the valve portion 5. The upper portion of the block C is provided with an exhaust pipe E which communicates with an exhaust port 17 leading to an arcuate, and preferably duplex passages 18 and 18' around a por-

tion of the bore 2 of the cylinder, said passages 18 and 18' being approximately midway the ends of the bore 2.

The lower portion 5 of valve V has a plurality of peripheral intake ports 19, 19 formed therein at points slightly below the upper end of the portion 5, and arranged for communication at regular intervals with the intake ports and passage 16. The upper portion 4 of the valve V has two series of openings 20 and 20' which are adapted to register at intervals with the exhaust passages 18 and 18' of the cylinder C, through which the burnt gases may be exhausted to pipe E. 15 Also, the portion 4 of the valve V has a plurality of elongated channels 21, 21, etc., longitudinally disposed on the portion 4 of the valve, and spaced apart, said channels being open at the lower end of the portion 4 and closed at their upper ends so as to afford communication between the lower bore 7 of the valve V and the storage chamber 9' of the cylinder C, at proper times for transferring the charges of fresh gas from the 20 lower bore of the sleeve valve to said storage chamber.

The piston P is provided with rings r , r , etc., on the upper portion 8 thereof, and rings r' , r' , on the lower portion 9 thereof for frictional engagement, respectively, with the bores 6 and 7 of the sleeve valve V, whereby the valve may be packed against leakage during the operation of the engine. The valve V is provided on its lower end 35 with a pair of lugs 22 and 22' diametrically spaced apart and alined with each other and adapted to receive and hold pins or screws 23 and 23'.

The crank case B is provided with a pair 40 of main bearings 24 and 24' which are carried in elongated bosses 25 and 25' formed on the crank case, and are adapted to receive a crank shaft S, as shown in Fig. 4. Said crank shaft is provided with a pair of eccentrics 26 and 26' which carry yokes 27 and 27' of the usual character, having arms 28 and 28' thereon, which pivotally connect with the pins 23 and 23' of valve V at the upper 45 bosses 29 and 29', so that the sleeve valve V will be reciprocated during the rotation of the shaft S.

The piston P is operatively connected with the crank shaft S by means of a connecting rod R, which is journaled at 30 on a crank 55 pin 30' centrally formed on the shaft S between portions 31 and 31'. Said connecting rod has a boss 32 at its upper end which carries a wrist pin 33 extending into bosses 34 and 34' formed internally of the upper portion 8 of piston P. Thus, the piston P is reciprocated within the sleeve valve V during the rotation of crank shaft S by the means described.

It will be understood at this point that 60 while we have shown only a single cylinder,

the engine may be modified so as to include a plurality of cylinders with substantially the same arrangement as in other engines.

The bore 3 of cylinder C is continued at its upper end and in the form of an annular space 35, for receiving the upper end of the portion 5 of valve V, when said valve approaches its uppermost limit of travel, and grooves 36, 36 are formed in the wall 13 of the cylinder to permit the movement of the 75 ribs 6' of valve V in such case.

Now, in operation, assuming that the piston P is initially positioned at its uppermost limit of movement, and a charge of gas has been previously admitted to the storage 80 chamber 9' and combustion chamber 15 in the head of the piston, the same having been compressed on the previous up-stroke of the piston, the portion 4 of the sleeve valve will be so positioned that communication between the storage chamber 9' and the major bore 3 of the cylinder will be closed by means of the upper end of said portion 4 engaging the upper portion of the cylinder 13 below the storage chamber 9', so as to hold 85 the gas compressed in readiness for a power stroke. When the firing of the gas takes place, either just before or subsequent to the position of the piston as stated, the piston will move downwardly under the impact, by reason of the power applied, for a slight distance, before the intake ports 19 of valve 90 V move into registration with the intake port 16 of the cylinder, and the suction within the bore 7 of valve V and above the portion 9 of piston P induces a flow of gas through said ports into the bore 7 during the continued down stroke of the piston.

As said piston approaches its lowermost limit of movement the valve V moves upwardly and closes the intake port 16 simultaneously with the piston reaching its lowermost limit of action, and also moves the exhaust ports 20 and 20' in the portion 4 of said valve into registration with the exhaust passages 18 and 18', so that as the piston begins to move upwardly in the cylinder, the upper bore 6 of the valve will be scavenged gradually during the ascent of the piston of the burnt gases therein.

Up to this point it will be understood that the storage chamber 9' is closed against communication with the bore 7 of the valve by means of the upper end of the valve V. As the piston gradually rises in the bore 6 of valve V, the lowermost exhaust port 20' in said valve is closed by the piston, but the uppermost ports 20 remain in registration with the uppermost passage 18 for exhausting the burnt gas from the bore 6 until such time as the head of the piston is substantially alined with said uppermost ports 20, whereupon the valve V on its ensuing downward movement in the bore 2 of the cylinder, and the upper portion 8 of the piston, closes 110

the ports 20 in the valve, just prior to the closing of the uppermost passage 18 by said valve.

Now, it will be understood that as the pis-

5 ton moves upwardly in the valve from its lowermost extreme of action, the valve also moves upwardly so as to close the intake port 16 and to open the storage chamber 9' to communication with the bore 7 of the valve 10 by means of the channels 21, 21 on the upper portion of said valve. Thus, the fresh gas which has been initially stored in the annular chamber surrounding the portion 8 of the piston, is compressed by the portion 9 15 of the piston as the piston is moved upwardly, and said gas is transferred from the bore 7 of the valve to the storage chamber 9'. Said storage chamber 9' in such case, is closed at its upper side by the valve portion 20 4 until the burnt gas has been exhausted, whereupon the valve V moves downwardly for establishing communication between the chamber 9' and a combustion chamber 15 at the head of the piston. As the piston nears 25 its uppermost limit of travel the chamber 9' is closed from communication with the bore 7, and the head of the piston compresses the charge of gas in the combustion chamber 15 and storage chamber 9'; preparatory to a 30 second power stroke.

Thus, it will be noted that at each revolution of the crank shaft a power impulse is provided for the piston P and simultaneously therewith a fresh charge of gas is admitted to the bore 7 of the valve. Likewise, at each reverse or upward stroke of the piston the fresh gas is initially compressed in the bore 7 simultaneously with the scavenging of the bore 6 of the burnt gas, and while 40 the fresh gas is under compression it is transferred to the storage chamber 9' and is finally compressed in the combustion chamber 15 in the final movement of the piston to its uppermost limit of travel.

45 It will be noted in connection with the description of our invention and the drawings appertaining thereto, that the movement of the sleeve valve V is but slight compared to the movement of the piston P, and is only sufficient to effect a complete opening and closing of the intake and exhaust ports and of the storage chamber. Also, said valve is connected with the crank case shaft in a proper relation with the piston, for effecting the proper operation of the engine as described.

By means of the structure described the crank case is not employed for compressing gas, as in other types of two-cycle engines, 50 and no intermediate storage chamber is employed between the intake and the compression chamber, as in still other types. The storage chamber 9' in my invention is substantially an enlargement of the combustion chamber 15, and not otherwise, and is disas-

sociated from the combustion chamber 15 only during the scavenging operation so as to prevent a mixture of the fresh and burnt gas.

What we claim is:

1. An internal combustion engine embodying a cylinder having two concentric bores of different diameter, a duplex sleeve valve reciprocable therein and having cylindrical portions corresponding in diameter to the bores in said cylinder, a duplex piston reciprocable internally of said sleeve valve, and having cylindrical portions corresponding in diameter to the bores of said valve, intake means arranged for communication with the larger bore of said valve, an annular gas storage chamber above and in communication with the smaller bore of said cylinder, and peripheral channels on the smaller portion of said valve affording communication between said storage chamber and the larger portion of said valve, and means for reciprocating said valve and said piston whereby a charge of gas admitted to the larger bore of said sleeve may be transferred to said storage chamber and compressed during the upward movement of said piston, preparatory to a power stroke.

2. An internal combustion engine embodying a cylinder having two concentric bores of different diameter, a duplex sleeve valve reciprocable therein and having cylindrical portions corresponding in diameter to the bores in said cylinder, a duplex piston reciprocable internally of said sleeve valve, and having cylindrical portions corresponding in diameter to the bores of said valve, intake means arranged for communication with the larger bore of said valve, an annular gas storage chamber above and in communication with the smaller bore of said cylinder, and peripheral channels longitudinally disposed on the exterior of the smaller portion of said valve affording communication between said storage chamber and the larger portion of said valve, means for reciprocating said valve and said piston whereby a charge of gas admitted to the larger bore of said sleeve may be transferred to said storage chamber and compressed during the upward movement of said piston, preparatory to a power stroke, and cooperating means formed in said valve and said cylinder for scavenging the upper bore of said valve of the products of combustion simultaneously with the charging of the lower bore of said valve with fresh gas.

3. An internal combustion engine having a large and a small cylinder therein, a valve seat longitudinally aligned with and spaced from said small cylinder, an annular gas receiving chamber intermediate said gas seat, and said small cylinder, the sleeve valve having portions slidably fitting said cylinders, the piston having portions slidably fitting

said valve, means for admitting gas to the large bore of said valve on the power stroke of said piston, and means for transferring said gas to said receiving chamber on the exhaust stroke of said piston, said valves engaging said valve seat for closing communication between the receiving chamber and the upper portion of said valve during the exhaust operation, and arranged to establish communication therebetween subsequent to the exhaust operation for compressing the gas preparatory to the power stroke.

4. An internal combustion engine including a sleeve valve having longitudinally aligned portions of different diameter, each of said portions provided with a plurality of peripheral ports and openings at the junctions of said portions, the smaller portion being provided with longitudinally formed channels in the periphery thereof closed at their upper ends, and open at the junction with the larger portion, for the purpose described.

5. An internal combustion engine comprising a cylinder block having aligned cylinder bores of different diameter, a sleeve valve reciprocable therein having correspondingly formed portions of different diameter, a piston reciprocable in said valve and having correspondingly formed portions of different diameter, the combustion chamber formed above the smaller cylinder and communicating with the smaller portion of said valve, a fuel inlet for the lower cylinder, and channels formed on the external periphery of the smaller portion of said valve for affording communication between said combustion chamber and said larger cylinders, and means formed at the junction of the large and small portions of said valve for admitting gas from said inlet to the larger portion of said valve, for the purpose described.
